CUTTING DEVICE

John T. Gondek, St. Paul, Minn., assignor to
 Gondek-Dixon Corporation, Somerville, Mass.,
 a corporation

Application November 12, 1934, Serial No. 752,578

1 Claim. (Cl. 82—1)

This invention relates to a cutting device to cut down the size of a battery terminal post in order that it may receive a standard size cap.

In order to prevent acid corrosion reaching the 5 terminal post of a battery, a cap with a wide bottom is used to cover the post and the cable clamped onto the cap. Inasmuch as batteries are not ordinarily furnished with such a cap, it is usually necessary to reduce the diameter of 10 the post to receive the cap, and I have provided a cutting device for that particular purpose.

One object of my invention is to provide such a 15 cutting device that is simple and compact in construction and operation. Another object is to provide such device with a removable blade, and also one whose cutting edge may be adjusted as desired. Still another object is to make said device operable by a well known tool such as a wrench.

20 The foregoing and other objects which will appear as the nature of the invention is better understood, may be accomplished by a construction, combination and arrangement of parts such as is disclosed by the drawing. The nature of 25 the invention is such as to render it susceptible to various changes and modifications, and, therefore, I am not to be limited to the construction disclosed by the drawing; but am entitled to all such changes therefrom as fall within the scope 30 of my claim.

In the drawing:

Figure 1 is a side elevation view illustrating my cutting device, showing the wrench to turn it and the terminal post of the battery in dot and 35 dash lines.

Figure 2 is a plan view of my cutting device showing the rectangular opening through the top to receive the wrench.

Figure 3 is a sectional view taken on the line 40 3—3 of Figure 1.

Figure 4 is an enlarged perspective view of the blade for my cutting device.

Figure 5 is a sectional view taken on the line 45 5—5 of Figure 1.

As illustrated, my cutting device consists of a 50 body portion 12 which has a rectangular opening 13 formed through the top to receive the end 26 of a crank wrench 25, or other tool, later referred to. Said body portion 12 also has an inwardly 55 tapering opening 14 through the bottom, the tapering corresponding with the taper of the battery post 28, later described, so that when the cutting operation is completed my device will be at the bottom of said battery post 28. Said opening 14 widens or flares outwardly as at 15 at the 60 outside, thereby providing more room in said opening 14 to locate my device over the battery post. There is a side opening 16 in the lower part of said body portion 12 through which the

60 shavings cut from the battery post may pass out.

A blade 18 which does the actual cutting rests against a recessed surface 17 in the body portion 12 at one side of said side opening 16, the back of said blade resting against a shoulder 19 which forms the end of said recessed surface 17. Said blade has slots 20 in its back portion through which screws 21 pass and screw into said body portion 12 to hold the blade in place flush against the recessed surface 17 with the beveled knife or cutting edge 22 projecting beyond said recessed surface 17 into said opening, as illustrated in Figure 3 of the drawing. One end of said blade 18 is chamfered as at 23 to correspond with the wider mouth portion 15 of said bottom opening 14 thereby providing a continuation of said cutting edge 22, so that my cutting device can start the cutting action at said wider mouth 15 with the projecting cutting edge of said chamfered portion if the top of the battery post is too large 20 to enter into said bottom opening 14.

It will be noted that my cutting device is very compact, and in order to do the cutting of the battery post it is necessary to provide some sort of a handle to rotate it such as a crank wrench 25 shown in Figure 1 of the drawing, which has a 25 rectangular end 26 to fit into the rectangular opening 13. In order to illustrate the position of my cutting device just before starting the cutting operation I show a battery 27 with a tapered battery post 28 in Figure 1 of the drawing ready 30 to receive my cutting device and be cut down to a size that will accommodate a standard size cap. These battery posts will vary a little in size, and as it is desired to make the caps of one standard size, practically every post has to be cut some- 35 what.

In order to remove said blade 18 the screws 21 are loosened and the blade taken out through the side opening 16, and in the event of the cutting edge becoming worn said blade may be set 40 inwardly a short distance from said shoulder 19.

What I claim is:

A cutting device comprising a body portion having an opening through the bottom, an opening through the side extending into said bottom opening, the outside mouth of said bottom opening being larger than the remainder of said opening, and a recessed portion at one end of said side opening, said recessed portion terminating in a shoulder portion at the outside of said recessed 50 portion, a blade in said side opening and bearing against said recessed portion and shoulder portion having its outside end chamfered to correspond with said outside mouth, said blade embodying a cutting edge projecting beyond the 55 interior surface of said body portion into said bottom opening and outside mouth, and means extending from said side opening into said body portion to hold said blade in position.
